US0D1028236S

(12) **United States Design Patent** (10) **Patent No.:** **US D1,028,236 S**
(45) **Date of Patent:** **** May 21, 2024**

(54) **ROUND NEEDLE HEAD**

(71) Applicant: **NanoPass Technologies Ltd.**, Ness Ziona (IL)

(72) Inventors: **Gal Admati**, Kibbutz Dorot (IL); **Yotam Levin**, Ness Ziona (IL)

(73) Assignee: **NanoPass Technologies Ltd.**, Ness Ziona (IL)

(**) Term: **15 Years**

(21) Appl. No.: **29/812,015**

(22) Filed: **Oct. 19, 2021**

(51) **LOC (14) Cl.** **24-02**

(52) **U.S. Cl.**

USPC **D24/146**

(58) **Field of Classification Search**

(57) **CLAIM**

The ornamental design for a round needle head, as shown and described.

DESCRIPTION

FIG. 1 is a front right perspective view of a round needle head, showing our new design;

FIG. 2 is a front right perspective view of the round needle head thereof;

FIG. 3 is a front view thereof;

FIG. 4 is a rear view thereof;

FIG. 5 is a top view thereof;

FIG. 6 is a left-side view thereof; and,

FIG. 7 is a right-side view thereof.

The broken lines shown in FIG. 1 illustrate environment and additional needle heads that form no part of the claimed design.

1 Claim, 3 Drawing Sheets
